FIG SLICING MACHINE

Henry Krum, Fresno, George Preall, Fowler, and James H. Chambers, Fresno, Calif., assignors to said James H. Chambers, Fresno, Calif.

Application July 6, 1931, Serial No. 548,768

1 Claim. (Cl. 146—98)

This invention relates to a machine for slicing figs, and to one particularly designed for use in connection with the fig inspecting system shown in the co-pending application for patent of 5 Messrs. Holmes and Clarke, Serial No. 547,660, filed June 29, 1931. This system deals with the cutting up for inspection purpose, of whole dried figs for conversion into fig paste and similar products, and we have found that cutting the 10 figs into thin slices greatly facilitates their inspection and permits of a more accurate inspection with a minimum of labor.

The principal object of the present invention is to provide a machine for cutting the figs into 15 thinner slices than can be obtained with any machine previously available, and so constructed that all the slices will be positively separated from each other. This enables the entire 20 sectional area of each slice to be subsequently fully exposed to the eyes of the inspectors, without the necessity of the slices being manually pulled apart to complete their separation, and minimizing the chances of infected or damaged slices being overlooked in the inspection.

25 By reason of the fact that the slices are thin, the probability of all infected areas being exposed is obviously much greater than with thick slices, since the likelihood of an infected portion being entirely concealed within a slice and invisible 30 from its outer faces is reduced to a minimum.

As a result of the actual use of this slicing machine, we have found that the subsequent inspection of the slices may be so easily, quickly and properly accomplished that it is possible to 35 use a low grade of figs which heretofore had been considered useless for this purpose, with a minimum of labor for inspection and still produce an ultimate product which will meet the most severe government tests for quality, and also the 40 finished product will present as attractive an appearance as if only the finest appearing figs were used in its manufacture.

A further object of the invention is to produce 45 a simple and inexpensive device and yet one which will be exceedingly effective for the purpose for which it is designed.

These objects we accomplish by means of such 50 structure and relative arrangement of parts as will fully appear by a perusal of the following specification and claim.

In the drawing similar characters of reference indicate corresponding parts in the several views:

Fig. 1 is a side elevation of the slicing machine.
Fig. 2 is a sectional elevation of the same.

Fig. 3 is a fragmentary sectional plan taken on the line 3—3 of Fig. 2.

Referring now more particularly to the characters of reference on the drawing, 1 denotes a pair of transversely spaced vertical side frames, 60 which are mounted on horizontal beams 2 or the like between which the endless inspection belt 3 is disposed. Mounted on top of the frames are horizontally spaced pairs of journal boxes 4 in which shafts 5 are mounted. These shafts support the slicing mechanism to be described later. The shafts are individually driven at different speeds and so that their upper peripheries turn toward each other by suitable means such as separate electric motors 6, mounted to one side of 70 the frame, and operatively connected to the shafts outside the frames by suitable gearing, as indicated at 7. One pair of journal boxes and the corresponding motor are mounted for horizontal movement along the frames so that the 75 distance between the shafts may be altered.

Mounted on said shafts between the frames is a plurality of thin cutting discs 8, whose edges are ground from both sides, those on one shaft being arranged in overlapping relation to those 80 on the other shaft. The discs are all spaced an equal distance apart, those on one shaft being disposed centrally between those on the other shaft. The spacing is preferably such that the distance between adjacent discs of the two shafts 85 is approximately a quarter of an inch. This has been found to be the best thickness for fig slices, but it is to be understood that if used to slice other products, it might be found desirable to alter 90 this spacing.

The use of two rows of cutting discs enables thinner slices to be cut than could be practicable with a single row of discs, and also causes the cutting unit to clean itself by centrifugal action.

The discs on each shaft are held separated 95 by spacer discs 9 each having a peripheral groove 10 into which the edge of the corresponding cutting disc on the opposite shaft projects.

This arrangement is plainly shown in Fig. 3. 100 This is a very important feature, since the spacers are relatively thick or wide compared to the cutting discs, and form stops or supporting shoulders for the figs being cut; and the cutting edges of the discs projecting inwardly of said stops, 105 the figs are necessarily cut completely through. The discs turning at different speeds gives them a shearing action through the fruit, which enhances the effectiveness of the cutting action. One shaft being capable of adjustment toward 110

the other, permits of the proper positioning of the cutting discs relative to the spacer grooves being maintained even after the cutting discs have been worn down from use and are smaller 5 in diameter than their original size.

The cutting and spacing discs are clamped together and in driving relation with their shafts by end collars on the shafts which are engaged by nuts 12 screwed onto the shafts inwardly of 10 the journal boxes. The cutting structure is boxed in by an enclosure 13 projecting upwardly from the frames 1 inwardly of the adjusting nuts 12. On top of the enclosure and over the discs is a feed hopper 14 into which the figs to be cut are 15 fed from a chute 15. To aid in feeding the figs into cutting relationship with the discs, a ratchet surfaced feed roll 16 is disposed between the top of the disc and the bottom of the hopper in parallel relationship to the discs toward one side 20 of the hopper or centrally between the discs. This roll, as will be noted from Fig. 2 of the drawing, while positioned at one side of the hopper 14 lies centrally between the two sets of cutting discs 8, and in relatively close proximity thereto, so that the distance between the roll 25 and either set of discs is less than any diameter of the figs to be cut by the discs. This position and spacing is of distinct importance in the invention. The prime objective of our invention 30 is to cut the dried figs into thin uniform slices so that they may be laid out in unbroken relation for inspection purposes. They must therefore not be hashed, chopped or ground up. Thus in our invention as the soft dried figs feed down 35 from the hopper 14, individual figs are contacted by the roller 16 and pressed into the adjacent set of cutting discs 8. Since the space between the roller and the set of cutting discs is insufficient for the fig to loosely pass between the same 40 the pressing action of the roller causes the adjacent set of discs 8 to make initial slicing cuts into the figs thus definitely starting the slicing action. The roller then holds the figs empaled on the cutting discs 8 until they are carried to the adjacent co-operating set of cutting discs 45 moving in the opposite direction. These co-operating sets of discs then start the intermediate slicing cuts into the figs and this double slicing action is completed as the figs move through the 50

sets of discs. At no time after the initial slicing cuts are made in the fig can it shift or turn from position so that the final effective thin and positive slicing action is assured. The shaft 17 of this roll is rotated at a speed less than that of the discs and in a direction so that its upper periphery turns down and toward the opposite side of the hopper. This rotation may be accomplished by any suitable means, such as a chain drive 18 connecting the shaft 17 with the 80 relatively fixed shaft 5.

To keep the discs in a non-sticky condition, perforated hot water and steam pipes 19 extend transversely of the enclosure to spray against the adjacent surfaces of the discs. The 85 enclosure at its ends extends down between the side frames 1 and at one end terminates above the belt so as to allow the figs dropping onto the same from between the cutters to pass into the open from under the enclosure without any interference. 90

From the foregoing description it will be readily seen that we have produced such a device as substantially fulfills the objects of the invention 95 as set forth herein.

While this specification sets forth in detail the present and preferred construction of the device, still in practice such deviations from such detail may be resorted to as do not form a departure 100 from the spirit of the invention, as defined by the appended claim.

Having thus described our invention what we claim as new and useful and desire to secure by Letters Patent is:

A fig slicing machine comprising horizontally 110 disposed co-operating sets of cutting discs rotatable toward each other, means to feed figs adjacent one set of discs, a feed roller disposed parallel to the discs and in relatively close proximity thereto so that the space between the roller 115 and discs is less than any diameter of the figs, such roller functioning to first press the figs into one set of discs to effect initial slicing cuts and maintaining the figs empaled on the discs in that partially cut position until they are carried into 120 engagement with the co-operating set of discs.
